FIG. 1 is a bottom plan view of the blank of a disposable receptacle for pet excrement showing my new design;
 FIG. 2 is a top plan view of the assembled but flattened receptacle;
 FIG. 3 is a bottom plan view of FIG. 2;
 FIG. 4 is a perspective view of the assembled receptacle with the rear closed and the scoop open;
 FIG. 5 is a top plan view of FIG. 4;
 FIG. 6 is a bottom plan view of FIG. 4;
 FIG. 7 is a front view of FIG. 4;
 FIG. 8 is a rear view of the FIG. 4;
 FIG. 9 is a side view of FIG. 4;
 FIG. 10 is a front perspective view with the rear closed and the scoop closed;
 FIG. 11 is a top plan view of FIG. 10;
 FIG. 12 is a bottom plan view of FIG. 10;
 FIG. 13 is a front view of FIG. 10;
 FIG. 14 is a side view of FIG. 10;
 FIG. 15 is a bottom plan view of the blank for a second embodiment of FIG. 1;
 FIG. 16 is a top plan view of the assembled but flattened receptacle of FIG. 15;
 FIG. 17 is a perspective view of the assembled receptacle of FIG. 16 with the rear closed and the scoop open;
 FIG. 18 is a top plan view of FIG. 17;
 FIG. 19 is a side view of FIG. 17;
 FIG. 20 is a front perspective view of the receptacle of FIG. 16 with the rear closed and the scoop closed; and,
 FIG. 21 is a front view of FIG. 20.
